UNITED STATES PATENT OFFICE.

DANIEL HAYNES, OF SEALY, TEXAS.

METHOD OF MAKING MATTRESSES.

SPECIFICATION forming part of Letters Patent No. 399,041, dated March 5, 1889.

Application filed September 29, 1888. Serial No. 286,764. (No model.)

To all whom it may concern:

Be it known that I, DANIEL HAYNES, a citizen of the United States, residing at Sealy, in the county of Austin and State of Texas, have 5 invented certain new and useful Improvements in Methods of Making Mattresses; and I do hereby declare that the following is a full, clear, and exact description of the same, reference being had to the annexed drawing, making a part of this specification, and to the letters and figures of reference marked thereon.

This invention relates to certain new and useful improvements in the art of manufacturing mattresses or the bats therefor; and it has 15 for its object to so construct the bat that it will not lump or wad into knots and hollows from use.

The novelty consists in the peculiar method of producing the bat, all as more fully herein- 20 after described, and then particularly pointed out in the claim.

I have illustrated in the drawing, in vertical longitudinal section, the preferable form of apparatus for carrying out my process, but 25 of course do not restrict myself to such construction.

The bat is formed by throwing the material for the same into a suitable receptacle by a current of air created by a machine, which at 30 the same time separates the fibers of the material of which the bat is composed, the material being compressed by suitable mechanism. By this method the material is evenly distributed, and, falling in separated particles 35 one after another, is so crossed and interlocked that a complete bat is formed that is free from lumps and that requires no tacking or quilting to hold it together.

Referring to the details of the drawing by 40 letter, A represents the box, of any suitable depth and of a size in cross-section to correspond to the size of the mattress. This box has hinged ends B; but either one or both of the ends may be hinged, as preferred, through 45 which the bat may be taken out to be placed in the tick, which is afterward sewed. The hinged end or ends may be held closed in any suitable manner—for instance, by means of a button at the lower edge that engages a 50 socket in the bed on which the bat is formed.

To one end of the box A is attached an ex-

tension, A', provided with a hopper, C, and in which is journaled the shaft a, carrying a plurality of saws, D, a grating, E, being arranged over the saws and extending between the same and upon each side thereof. This grating serves to take from the saws all lint not held by the teeth thereof, that only being fit to be passed to the brush hereinafter described, which takes it from the saws and 60 passes it by a draft of air, which its velocity has created, into the receptacle A.

F is a brush carried by the transverse shaft b, and G is the main drive-pulley on the shaft c. Any suitable means may be employed to impart to the saws and brush the necessary rotary motion—such, for instance, as belts and pulleys, as represented by dotted lines in the drawing.

H is a flue or opening connecting the box 70 or extension A' with the receptacle A, as shown, and through this opening the material is forced into said receptacle.

I is a fan hinged or connected in any well-known way to a bracket, a, or to any other 75 fixed portion of the frame of the machine, and is operated by means of a pitman, K, which is eccentrically connected to the wheel G, which is driven by any suitable power.

The bottom of the receptacle A should be 80 constructed in such a manner that after the bat is completed it can be easily withdrawn. This may be accomplished in various ways; but I prefer to form said bottom of strips, the alternate ones being fixed, the others movable, having one end framed together and extending outside the receptacle, by which the bat for the mattress is withdrawn from the receptacle and upon which it rests. 85

The top L is made heavy and is preferably 90 formed with apertures to admit of the escape of dust and excess of air, and is arranged to be lowered upon the bat for the purpose of compressing the same. This may be done in any well-known way.

In operation the material, which may be 95 wool, moss, hair, cotton, or shucks, or other material suited for the purpose, or any two or more of the same mixed, is fed into the hopper C, where it is taken up by the saws D and properly acted upon to separate the fibers and deliver them to the brush F, and by said 100

brush, which revolves at a proper speed, the material is forced through the flue H into the receptacle A. The brush F, which is a combined brush and fan, serves not only to deliver the fibers from the saws, but creates a current of air strong enough to force the disintegrated material into the receptacle, where it is evenly distributed by means of the fan I. When sufficient of the material has been forced into the receptacle, the machine is stopped and the cover or follower L lowered upon the material and in any suitable manner made to compress the same.

What I claim as new is—

15 The improvement in the art of manufac-

ting mattress-bats, which consists in first disintegrating the material and simultaneously forcing the same into a suitable receptacle, fanning said material as it passes into the receptacle, and finally compressing the same, 20 substantially as described, thereby dispensing with tacking of the bat, as set forth.

In testimony that I claim the above I have hereunto subscribed my name in the presence of two witnesses.

DANIEL HAYNES.
